Patented Apr. 20, 1976

239,627

SHOWER STALL

Bruno Verlet, Mourenx, France, assignor to Consortium
Pyrenees Plastiques, Mourenx, France

Filed Sept. 6, 1973, Ser. No. 394,622

Term of patent 14 years

Int. Cl. D23—02

U.S. Cl. D23—57

FIG.1

FIG. 2

FIG.3

FIG.4

FIG.5

FIG. 1 is a front elevational view of a shower stall showing my new design;

FIG. 2 is a left side elevational view thereof;

FIG. 3 is a top plan view thereof;

FIG. 4 is a bottom plan view thereof; and

FIG. 5 is a perspective view showing the right side thereof.

I claim:

The ornamental design for a shower stall, as shown.
